UNITED STATES PATENT OFFICE.

WILLIAM MOLLER, OF NEW YORK, N. Y.

FURNACE FOR DESULPHURIZING ORE.

SPECIFICATION forming part of Letters Patent No. 243,943, dated July 5, 1881.

Application filed December 31, 1880. (No model.)

To all whom it may concern:

Be it known that I, WILLIAM MOLLER, a citizen of the United States, residing at New York, in the county and State of New York, 5 have invented new and useful Improvements in Furnaces for Desulphurizing Ore, of which the following is a specification.

This invention relates to that class of metallurgic furnaces for desulphurizing ores in 10 which the ore is placed in a heated retort and currents of heated air passed through the retort in contact with the ore.

The invention consists in the combination, with a retort inclosed by a surrounding brick- 15 wall and projecting at its front end over the fire-chamber, by which the retort is heated exteriorly, of horizontal air-flues communicating with the external atmosphere at the rear wall of the furnace, and extending on opposite 20 sides of the retort to near the front wall of the furnace, along the sides of the fire-chamber, said air-flues thence returning rearwardly to or near the rear end of the inclosed retort and opening into vertical channels which communicate 25 with the interior of the retort at its rear end, as will be fully hereinafter described in detail, whereby the retort is highly heated by the products of combustion from the fire-chamber, which circulate freely around the exterior 30 of the retort, and at the same time the external atmosphere entering the horizontal air-flues at the rear wall of the furnace is carried forward along the retort and a portion of the side walls of the fire-chamber, and is thence 35 returned rearwardly and discharged in a highly-heated condition into the retort at its rear end, thereby promoting combustion of the sulphur, phosphorus, arsenic, and other like impurities contained in the ore without permitting 40 the smoke or products of combustion to come in direct contact with the ore.

This invention is illustrated in the accompanying drawings, in which Figure 1 represents a front elevation. Fig. 2 is a longitudinal vertical section in the plane $x-x'$, Figs. 1, 45 3, and 6. Fig. 3 is a horizontal section in the plane $y-y'$, Fig. 2. Fig. 4 is a similar section in the plane $z-z'$, Fig. 2. Fig. 5 is a transverse vertical section in the plane $x'-x''$, Fig. 2. Fig. 50 6 is a horizontal section in the plane $y'-y''$, Fig. 2.

Similar letters indicate corresponding parts.

In the example represented by these drawings I have shown two retorts inclosed in and supported by the same wall; but, if desired, only 55 one or more than two retorts may be placed into the wall without deviating from my invention.

In the drawings, the letter A designates the furnace-wall, which incloses and supports the 60 retort or retorts B B'. C C' are the fire-places, and D is the smoke-stack.

The retorts are constructed of fire-clay or any other suitable material, and they rest upon tiles $a a' b$, which are situated beneath the 65 central parts of the retorts, as shown in Figs. 2 and 4. The tiles $a a'$ are placed at certain distances apart, and the spaces $c c'$, which are formed beneath the retorts, communicate one with each of the fire-places C C'. The retorts 70 B B' are open at their front ends and closed at their rear ends, and from each of the spaces, c or c' , extends a flue, d or d' , up at the rear end of the corresponding retort, as shown in Fig. 2. On the top of each retort is placed a 75 row of tiles, $e e'$, Figs. 2 and 3, which support the brick wall above, and which leave open spaces $f f'$, which communicate at their rear ends with the upright flues $d d'$ and at their front ends with a flue, g or g' , extending to the smoke-stack D, Fig. 2. By these means the heated 80 products of combustion which escape from the fire-places circulate through the spaces $e e'$, flues $d d'$, and spaces $f f'$ around the retorts, and they escape through the smoke-stack without being permitted to enter into the retorts. 85

With each of the retorts B B' are combined two air-flues, $h h'$. These air-flues communicate with the open air at the rear wall of the furnace, (see Figs. 2 and 4,) and thence they 90 extend forward nearly to the front wall, and then backward to the rear ends of the retorts, and then up through vertical channels $h^* h'^*$, which communicate with the retorts near their rear ends through openings $i i'$, the course of 95 one of these channels being shown in dotted lines in Fig. 2, while portions of the air-flues are shown in Fig. 4, and the vertical channels $h^* h'^*$ are fully shown in Fig. 2. From this explanation it will be readily understood that 100 when the furnace is in operation the air which circulates through the air-flues $h h'$ becomes highly heated, and as it passes into the retorts in this heated state it serves very effectually

to promote the oxidation of sulphur, phosphorus, arsenic, and other like impurities which are or may be mixed with the ore contained in the retorts, said retorts, together with their contents, being heated up to a high degree by the products of combustion circulating round them through the flues *c c'*, *d d'*, *f f'*. The front ends of the retorts *B B'* open into the upright flues *g g'*, which lead into the smoke-stack, so that gases formed in the retorts pass off, together with the products of combustion. On the top of the furnace-wall *A* is placed a flat open pan, *F*, for the purpose of heating the ore before it is introduced into the retorts. This pan is provided in its front end with openings *j j'*, which can be opened and closed by suitable gates, *k k'*, Figs. 2 and 5. The openings *j j'* communicate with the upright flues *g g'*, which lead down into the retorts *B B'*. By opening the gates *k k'* the ore from the pan *F* can be readily dumped into the retorts, and it is pushed back and spread evenly on the bottoms of said retorts by suitable rakes, which are introduced through openings *l l'*, Figs. 1, 2, and 6, which are provided with doors *m m'*, so that they can be opened and closed as may be required.

Access can be had to the fire-places through openings *n o*, Figs. 1 and 2, which are closed by suitable doors. Those portions of the furnace-wall which are exposed to the direct action of the heated products of combustion are made of fire-clay or fire-bricks, the same as the retorts.

The principal advantage derived from the construction of my furnace is due to the fact that the heated products of combustion which rise from the fire-places are not permitted to come in direct contact with the ore in the retorts, while at the same time currents of highly-heated air are caused to pass through the

Heretofore a desulphurizing apparatus has been constructed of a furnace, a cylindrical retort arranged within the furnace and containing a spiral blade for conveying the ore through the retort, and a pipe coiled around the retort within the furnace, and from which a blast of hot air is forced into and through the said retort; but such structure does not constitute my invention. 45 50

Ovens have also been constructed of brick-work, with flues extending through the brick-work around the oven-chamber, and connecting the latter with the furnace; but neither 55 does such structure constitute my invention.

I do not claim as my invention the process of treating ore in a heated retort or muffle to which cold air is admitted.

What I claim as new, and desire to secure 60 by Letters Patent, is—

In a metallurgic furnace, the retort *B*, inclosed by the surrounding brick wall *A*, with its forward end projecting over the fire-chamber and communicating with the smoke-stack, 65 in combination with the horizontal air-flues *h h'* communicating with the external atmosphere at the rear wall of the furnace and extending through the brick wall on opposite sides of the retort to near the front wall of 70 the furnace, along the sides of the fire-chamber, and thence returning rearwardly and opening into vertical channels which communicate with the interior of the retort at its rear portion, all substantially as shown and described. 75

In testimony whereof I have hereunto set my hand and seal in the presence of two subscribing witnesses.

WILLIAM MOLLER. [L. S.]
